US0D1023624S

(12) **United States Design Patent** (10) Patent No.: **US D1,023,624 S**
(45) Date of Patent: ** Apr. 23, 2024

(54) **COLLAPSIBLE WORKSTATION**

(71) Applicant: **AMQ Solutions, LLC**, Santa Clara, CA (US)

(72) Inventors: **Kin Fui Chong**, Jurong West (SG); **Tsung-Hsien Ho**, Taichung (TW); **Soo Beng Khoo**, Telok Blangah (SG); **Dennis Ding Yik Ming**, Selangor (MY); **Jiwon Shin**, Seoul (KR)

(73) Assignee: **AMQ Solutions, LLC**, Santa Clara, CA (US)

(**) Term: **15 Years**

(21) Appl. No.: **29/803,763**

(22) Filed: **Aug. 16, 2021**

(51) LOC (14) Cl. **06-03**

(52) U.S. Cl.

USPC **D6/642**

(58) **Field of Classification Search**

USPC D6/332, 641, 642, 643, 656, 714, 653, D6/654.21

CPC A47B 43/00; A47B 3/00; A47B 3/083; A47B 21/00; A47B 21/02

CLAIM

The ornamental design for a collapsible workstation, as shown and described.

DESCRIPTION

FIG. 1 is a top front/right perspective view of an embodiment of a collapsible workstation;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom/left perspective view thereof.

1 Claim, 6 Drawing Sheets
